UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, NEW YORK.

ACTUATING MECHANISM.

1,258,379.

Specification of Letters Patent.

Patented Mar. 5, 1918.

Application filed August 20, 1917. Serial No. 187,141.

To all whom it may concern:

Be it known that I, CHARLES C. TOMKINSON, a citizen of the United States of America, and a resident of Plainfield, Union 5 county, and State of New Jersey, have invented certain new and useful Improvements in Actuating Mechanism, of which the following is a specification, reference being had to the accompanying drawings, forming 10 a part thereof.

My invention relates to actuating mechanism and its object is to provide a simple device by means of which a driven element such for example as a shaft, may be driven 15 by a motor or moved by hand without the possibility of either the motor or the hand-operated device interfering with each other.

Another object is to provide a manually operated auxiliary mechanism for a motor- 20 driven member which may be used whenever the motor cannot be used and to make such auxiliary mechanism reversible.

Another object is to so construct and arrange the parts that either the motor or the 25 hand-operated device is inoperative when the other can be used.

A still further object is to so construct and arrange an auxiliary hand-operated device in such a manner that it will assume 30 automatically such a condition that when not in use it will not interfere with other means for actuating the driven member.

Another and more specific object of the 35 invention is to provide an improved ratchet mechanism.

In order that my invention may be thoroughly understood I will now proceed to describe the same in the following specification, and then point out the novel features 40 thereof in appended claims.

Referring to the drawings:

Figure 1 is a front elevation of a wheeled frame with driving mechanism therefor which is made according to and embodies 45 my invention.

Fig. 2 is a plan view of the same apparatus.

Fig. 3 is a front elevation partly in section and drawn on a larger scale, of a part 50 of the driving mechanism shown in the preceding figures.

Fig. 4 is an end elevation of a detail of construction, this figure illustrating a holding bracket.

55 Fig. 5 is an end elevation on a still larger

scale, of the improved ratchet mechanism, certain parts being shown in section.

Fig. 6 is a front elevation of the ratchet mechanism.

Like characters of reference designate corresponding parts in all the figures.

10 designates a frame upon which the different parts of the apparatus are supported. 11 designates wheels on which the frame rests and 12 tracks for the wheels. 60 Each pair of wheels is affixed to a journal 13 on each of which is a worm gear 14, and worms 15 on a shaft 16 mesh with these worm gears so that when shaft 16 is rotated in one direction or the other, the 70 wheels 11 will be rotated and the whole apparatus moved to the left or to the right on the tracks 12. 17 is a part of the frame 10 which forms an operator's platform.

20 is a reversible electric motor mounted 75 on the frame 10. 21 is a magnetic brake and 22 a controller for the motor near the operator's platform 17. The end of the motor shaft 23 is square and the socket 41 of a pinion 42 fits over it. This pinion transmits 80 the rotation of the motor at a reduced rate to the shaft 16 through a train of gears 24, one of which 25 is affixed to the shaft 16. By means of this arrangement the motor may be used to move the apparatus on the 85 track in either direction.

26 is a bracket for holding the hand lever 40 on the end of which is pinion 42 in alignment with the motor shaft. This forms a bearing, the cap of which, designated by 27 90 is pivoted at 28 and has a part 29 which overlaps the end of the hand lever and prevents the latter from moving off from the end of the motor shaft.

30 is a ratchet wheel affixed to the shaft 95 16 near the operator's platform. Rotatively supported on its hub is a ratchet arm 31 on which is loosely pivoted a pawl 32. 33 is a spring which in its full line position is so arranged that one of its ends presses the 100 pawl into engagement with a ratchet wheel. A part of the spring forms a straight shank 34 and its end is bent over at 36 and brought back as to form a part 37 parallel with the shank 34. This in Fig. 5 passes through a 105 hole 38 in the spring guide. 38^a is another hole in the spring guide for the reception of the part 37 when the spring is in another position. The upper end 39 of ratchet arm 31 is square in cross section and of the same 110

dimensions as the square end 23 of the motor shaft.

40 is a hand lever, one end of which is constructed to form the socket 41 which fits over 5 the end 23 of the motor shaft or over the end 39 of the ratchet arm. The end of this hand lever which surrounds the socket is enlarged as shown and gear teeth are made in it to form the pinion 42.

10 The operation of driving the mechanism by the motor is obvious and needs no specific description. If no motive power is available or if for any other reason the motor cannot be used, the hand lever 40 is removed 15 from the end of the motor shaft and put onto the end of the ratchet arm. Removing this member from the motor shaft completely disconnects the motor from shaft 16.

20 The socket end of the hand lever comes in contact with the bend 36 of the spring 33 and holds it against pawl 32. By oscillating the hand lever the ratchet wheel 30 and shaft 16 will be rotated in one direction to traverse the whole apparatus. If it is desired to traverse the apparatus in the other 25 direction, the hand lever is removed, the spring raised into the position indicated by broken lines at 33^A in Fig. 5, in which position the end of the part 37 is above the 30 spring guide 35, so that the spring may be turned over to the right. At this time the pawl 32 is turned over about its pivot to engage the teeth of ratchet wheel 30 on the other side of the pawl pivot and the spring 35 33 pushed down into engagement with the pawl with its part 37 in hole 38^A of the spring guide. The hand lever 40 is again applied to the ratchet arm to hold the spring in place and to enable the operator to rotate 40 shaft 16 in the opposite direction.

Another feature of this ratchet mechanism is that when the hand lever 40 is removed, the weight of the ratchet arm 31 tends to make the latter swing into a vertically downward position. The spring fits 45 loosely in the spring guide so that when the ratchet arm is in its inverted position the spring will drop down out of engagement with the pawl, thus automatically disconnecting the ratchet mechanism from the shaft 16.

Obviously, this invention is applicable to other mechanisms than that shown and described and I do not intend to limit myself 55 to any specific form or construction or application; for example, it is within the scope of this invention to have the completion of the hand operated device, disconnect the motor circuit. In fact, I intend no limitations 60 other than those imposed by the appended claims.

What I claim is:

1. A shaft, a ratchet wheel thereon, a ratchet arm, rotatable about said shaft, a 65 pawl pivoted on said arm, a spring slidably

supported on said arm and arranged when in one position to press the pawl into engagement with the ratchet wheel, and arranged to slide away from the pawl when the ratchet arm rotates to an inverted position to disengage the pawl from the ratchet wheel.

2. A shaft, a ratchet wheel thereon, a ratchet arm rotatable about said shaft, a pawl pivoted on said arm and movable 75 about its pivot into engagement with the ratchet wheel on either side of its pivot, a spring arranged to press the pawl into engagement with the ratchet wheel, and means on said arm for holding the spring 80 in different positions to press against one side or the other of the pawl.

3. A shaft, a ratchet wheel thereon, a ratchet arm rotatable about said shaft, a pawl pivoted on said arm and movable 85 about its pivot into engagement with the ratchet wheel on either side of its pivot, a spring arranged to press the pawl into engagement with the ratchet wheel, means on said arm for holding the spring in different positions to press against one side or 90 the other of the pawl, and a hand-lever arranged to be placed on the ratchet arm and to maintain the spring in one of its positions when in place.

4. A shaft, a ratchet wheel thereon, a ratchet arm rotatable about said shaft, a pawl pivoted on said arm and movable about its pivot into engagement with the ratchet wheel on either side of its pivot, 100 a spring arranged to press the pawl into engagement with the ratchet wheel, said spring having two parallel parts, a spring guide on said arm provided with a central opening for one of the parts of the spring 105 and two side openings for selectively engaging the other part of the spring, whereby the spring is held in two different positions to press against one side or the other of the pawl.

5. A shaft, a ratchet wheel thereon, a ratchet arm rotatable about said shaft, a pawl pivoted on said arm and movable about its pivot into engagement with the ratchet wheel on either side of its pivot, 115 a spring arranged to press the pawl into engagement with the ratchet wheel, said spring having two parallel parts joined by a bend, a spring guide on said arm provided with a central opening for one of the parts 120 of the spring and two side openings for selectively engaging the other part of the spring, whereby the spring is held in two different positions to press against one side or the other of the pawl, and a hand-lever 125 arranged to be placed on the ratchet arm and to engage the bend of the spring to maintain the spring in one or the other of its positions when in place.

6. A shaft, a ratchet wheel thereon, a 130

ratchet arm rotatable about said shaft, a pawl pivoted on said arm and movable about its pivot into engagement with the ratchet wheel on either side of its pivot, 5 a spring arranged to press the pawl into engagement with the ratchet wheel, and means on said arm for holding the spring in different positions to engage against one side or the other of the pawl, said spring 10 being radially slidable in the holding means away from the pawl when the ratchet arm rotates to an inverted position.

7. A shaft, a ratchet wheel thereon, a ratchet arm rotatable about said shaft, a 15 pawl pivoted on said arm and movable about its pivot into engagement with the ratchet wheel on either side of its pivot, a spring arranged to press the pawl into

engagement with the ratchet wheel, said spring having two parallel parts, a spring 20 guide on said arm provided with a central opening for one of the parts of the spring and two side openings for selectively engaging the other part of the spring, whereby the spring is held in two different positions to press against one side or the other of the pawl, said spring being radially slid- 25 able in the spring guide away from the pawl when the ratchet arm rotates to an inverted position.

In witness whereof, I have hereunto set my hand this 17 day of August, 1917.

CHARLES C. TOMKINSON.
